Primary Examiner — Susan E Krakower*Assistant Examiner* — Andrew Kerr(74) *Attorney, Agent, or Firm* — Bayramoglu Law Offices LLC(57) **CLAIM**

The ornamental design for a bread box, as shown and described.

DESCRIPTION

FIG. 1 is a front perspective view of a bread box showing my new design;

FIG. 2 is a front elevational view thereof;

FIG. 3 is a rear elevational view thereof;

FIG. 4 is a right side elevational view thereof, a left side elevational view being a mirror image;

FIG. 5 is a top plan view thereof;

FIG. 6 is a rear perspective view thereof; and,

FIG. 7 is a front perspective view thereof showing an opening state.

A bottom view of the bread box is not provided as it does not contain any ornamentality.
